UNITED STATES PATENT OFFICE.

CECIL M. WICKSTRUM, OF OMAHA, NEBRASKA.

KNEELING BENCH.

Application filed February 17, 1928. Serial No. 255,092.

This invention relates to a kneeling bench of the collapsible type, the primary object of the invention, being to provide a bench which may be readily and easily folded into a small and compact article, and one which may be readily extended and placed before a casket to permit mourners to kneel in prayer before the casket.

Another object of the invention is to provide a device of this character embodying hingedly connected sections, box-like in formation so that the sections act as a container for the cushion and covering or drapery, when the device is being transported or stored.

With the foregoing and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawing:

Figure 1 is a perspective view illustrating a kneeling bench constructed in accordance with the invention.

Figure 2 is a side elevational view thereof, the cover or drapery being shown in section.

Figure 3 is a longitudinal sectional view through the device in its closed position.

Figure 4 is an end elevational view of the kneeling bench, the drapery being shown in section.

Referring to the drawing in detail, the reference character 5 indicates rectangular sections, which are box-like in formation, the same being connected by means of hinges 6 which connect with the sections at points adjacent to their open sides so that when the sections are folded together, the open sides will move to positions adjacent to each other

providing a container for the pad and drapery or covering forming a part of the invention.

The cushion is indicated by the reference character 7 and is of a construction to cover the upper surface of the kneeling bench when the kneeling bench is in its extended position. The cushion or pad includes padded sections connected by cloth strips 8 so that one section may be folded upon the other in a manner as shown by Figure 3 and 55 closely fitted within the kneeling bench.

At the ends of the cushion are tabs 9 provided with snap fasteners 10 to be snapped over heads that are secured to the ends of the bench proper to hold the cushion in position. The drapery or covering may be of any desired design, the same being of a length to closely fit over the cushion and sections of the bench to cover the same as shown by Figure 1.

From the foregoing it will be obvious that due to the construction shown and described a bench is provided which may be extended and positioned with facility, and one which may be readily folded and packed for transportation when it has served its purpose.

It might be further stated that a latch member such as indicated at 11 is provided to secure the sections in their folded positions.

What is claimed is:

A kneeling bench including box-like sections, means for hingedly connecting the sections, cushions positioned over the sections when in their extended positions, means at 80 the outer ends of the cushions for securing the cushions to the bench, and a covering fitted over the cushions and bench when the bench is in its extended position.

In testimony that I claim the foregoing as 85 my own, I have hereto affixed my signature.

CECIL M. WICKSTRUM.
